A. THOMAS

COLLAPSIBLE RECEPTACLE

Filed May 27, 1925

Inventor
Arthur Thomas,

By *Clarance A. O'Brien*

Attorney

UNITED STATES PATENT OFFICE.

ARTHUR THOMAS, OF ADA, MICHIGAN.

COLLAPSIBLE RECEPTACLE.

Application filed May 27, 1925. Serial No. 33,190.

To all whom it may concern:

Be it known that I, ARTHUR THOMAS, a citizen of the United States, residing at Ada, in the county of Kent and State of Michigan, have invented certain new and useful Improvements in a Collapsible Receptacle, of which the following is a specification.

This invention relates to collapsible receptacles and has reference more particularly to the type known in the art as buckets or pails.

One of the important objects of the present invention is to provide a collapsible receptacle which may be readily folded in such a manner as to occupy a minimum amount of space when not in use, so as to permit the same to be stored away or easily carried.

The receptacle being further adapted to be easily and readily set up for use whenever necessary.

A further object of the invention is to provide a collapsible receptacle of the above mentioned character, wherein the same is adapted to be used by campers, tourists, and is further adapted to be carried in an automobile, a spout being associated with the receptacle to permit the radiator of an automobile to be filled when the receptacle is assembled.

A further object of the invention is to provide a collapsible receptacle of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

The figure represents a perspective view of the collapsible receptacle embodying my invention showing the same set up for use and with parts broken away.

In the drawing, wherein for the purpose of illustration is shown the preferred embodiment of my invention, the numeral 1 designates generally my improved collapsible receptacle and the same comprises the substantially rectangular frames 2 and 3 respectively, the same being formed of wire. The adjacent side edges of the wire frames 2 and 3 are hingedly secured together as illustrated at 4. The side of the frame 3

which is hinged to the adjacent side of the frame 2 is bent to provide the shoulders 5 for cooperation with the hinges 4 to prevent the displacement of the same from their proper positions adjacent the upper and lower portions of the frames.

The opposite side edge of the frame 3 has associated therewith the guide wire 6 which extends from the top of the frame to a point adjacent the intermediate portion of the frame and the purpose of the guide wire will hereinafter be more fully described. A wire bail such as is shown at 7 has the loops 8 and 9 formed at the respective ends thereof, the loop 8 being adapted for slidable engagement with the upper edge of the frame 2 while the loop 9 on the opposite end of the bail 7 is adapted for slidable engagement with the wire guide 6. A bend 10 is provided in the intermediate portion of the upper edge of the frame 2 as is clearly illustrated in the drawing for receiving the loop 8 of the wire bail 7 and when in this position, the opposite end of the wire bail 7 has its loop 9 disposed at the top of the wire guide 6 whereby the frames 2 and 3 are supported in spaced relation with respect to each other to provide a substantially triangular shaped frame.

The receptacle comprises a piece of canvas which is adapted to be disposed over the frames as well as over the space formed between the free side edges of the frames 2 and 3 as well as over the bottom of the triangular shaped frame formed in the manner above described. The fabric covering is designated by the numeral 11. In order to support the covering in position over the triangular shaped frame, the upper edge of the canvas covering is provided with eyes or openings 12 through which extend the rings 13, the latter being adapted for slid able engagement with the upper edges of the frames 2 and 3 respectively as is clearly illustrated in the drawing.

A pouring spout 14 is associated with the canvas covering 11 and when the canvas covering is supported in proper position over the triangular shaped frame, the spout will be located at one of the apices of the triangular shaped frame and at the top of the frame.

The wire 7 serves a two fold purpose in that the same provides a means for forming the triangular shaped frame and holding the same in an assembled position, and secondly

the wire provides a bail whereby the receptacle may be conveniently handled.

When not in use, the receptacle may be easily and readily collapsed by sliding the loop 9 on one end of the bail 7 downwardly on the wire guide 6 and causing the loop 8 on the other end of the wire bail to be moved along the upper edge of the frame 2. In this manner the receptacle will be folded 10 and may be stored away without occupying any considerable amount of space.

The provision of a collapsible receptacle of the above mentioned character, enables the same to be used for various purposes and 15 may be easily and readily set up for use whenever necessary.

While I have shown the preferred embodiment of my invention, it is to be understood that various changes in the size, shape 20 and arrangement of parts may be resorted to without departing from the spirit of the invention and the scope of the appended claims.

Having thus described the invention, 25 what is claimed is:—

1. A collapsible receptacle comprising a pair of rectangular frames hinged at their adjacent side edges, means for holding such frames in such a manner as to provide a substantially triangular shaped frame, a fabric 30 covering for the same, said aforementioned means adapted to provide a handle for the receptacle.

2. A collapsible receptacle comprising a pair of rectangular frames hinged at their adjacent side edges, means for holding such frames in such a manner as to provide a substantially triangular shaped frame, a fabric covering for the same, said aforementioned 35 means adapted to provide a handle for the receptacle, and a spout associated with the fabric covering.

3. A collapsible receptacle comprising a

pair of rectangular frames hingedly secured together at their adjacent side edges, 45 a wire extending between the upper edges of the frame in such a manner as to provide a substantially triangular shaped frame, and a fabric covering for the same.

4. A collapsible receptacle comprising a 50 pair of rectangular frames hingedly secured together at their adjacent side edges, a wire extending between the upper edges of the frame in such a manner as to provide a substantially triangular shaped frame, a fabric 55 covering for the same, said wire further providing a handle for the receptacle.

5. A collapsible receptacle comprising a 60 pair of rectangular frames hingedly secured together at their adjacent side edges, a wire extending between the upper edges of the frame in such a manner as to provide a substantially triangular shaped frame, a fabric covering for the same, said wire further 65 providing a handle for the receptacle, and a spout associated with the fabric covering.

6. A collapsible receptacle comprising a 70 pair of rectangular shaped frames hingedly secured together at their adjacent side edges, a guide wire on one of the free side edges of one of the frames, a wire bail having its respective ends looped for slidably engagement with the wire guide and the top edge of the other frame, said bail adapted to hold the frames in such a manner as to provide a 75 substantially triangular shaped frame when in one position with respect to the frames, a fabric covering for the triangular shaped frame, a spout associated with the covering, 80 said frames adapted to be folded when the wire bail is moved along the wire guide and the upper edge of the other frame.

In testimony whereof I affix my signature.

ARTHUR THOMAS.
